US00D837960S

(12) **United States Design Patent** (10) **Patent No.:** **US D837,960 S**
Liang (45) **Date of Patent:** **** Jan. 8, 2019**

(54) **HUMIDIFIER**

(71) Applicant: **ZHONGSHAN QUANGLI ELECTRIC APPLIANCES TECHNOLOGY CO., LTD.**
 Zhongshan, Guangdong (CN)

(72) Inventor: **Jingqing Liang**, Guangdong (CN)

(73) Assignee: **ZHONGSHAN QIANGLI ELECTRIC APPLIANCES TECHNOLOGY CO., LTD. (CN)**

(**) Term: **15 Years**

(21) Appl. No.: **29/633,020**

(22) Filed: **Jan. 11, 2018**

(51) LOC (11) Cl. **23-04**

(52) U.S. Cl. **D23/356**
 USPC .....

(58) **Field of Classification Search**

Primary Examiner — David G Muller

Assistant Examiner — Nathan M Johnston

(57) **CLAIM**

The ornamental design for humidifier, as shown and described.

DESCRIPTION

FIG. 1 is a front view of the humidifier showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.

1 Claim, 7 Drawing Sheets
